US00D929595S

(12) **United States Design Patent** (10) Patent No.: **US D929,595 S**
(45) Date of Patent: **** Aug. 31, 2021**

(54) **LIGHT SEAL COVER**

(71) Applicant: **MacuLogix, Inc.**, Harrisburg, PA (US)

(72) Inventors: **Gregory R. Jackson**, Hershey, PA (US); **David E. Beecher**, Shippensburg, PA (US); **David E. Orr**, Piedmont, SC (US); **Frank Jones**, Carp (CA); **Nathan Smith**, Lewistown, PA (US)

(73) Assignee: **MACULOGIX, INC.**, Harrisburg, PA (US)

(**) Term: **15 Years**

(21) Appl. No.: **29/706,613**

(22) Filed: **Sep. 21, 2019**

(51) LOC (13) Cl. **24-02**

(52) U.S. Cl.

USPC **D24/172**

(57) **CLAIM**

The ornamental design for a light seal cover, as shown and described.

DESCRIPTION

FIG. 1 is a perspective view of the ornamental design; FIG. 2 is a front view of the ornamental design; FIG. 3 is a back view of the ornamental design; FIG. 4 is a side view of the ornamental design; FIG. 5 is another side view of the ornamental design; FIG. 6 is a top view of the ornamental design; FIG. 7 is a bottom view of the ornamental design; and, FIG. 8 is a perspective view of the ornamental design as placed over a light seal. The broken lines illustrate portions of environmental structure and form no part of the claimed design.

1 Claim, 6 Drawing Sheets
